ROAD SWEEPING MACHINES

Hedley Benjamin Keogh, 7 Hammond St., Thornbury, Victoria, Australia, and Lancelot Douglas Ernest Ebeling, 58 Washington St., Toorak, Victoria, Australia

Filed Apr. 23, 1962, Ser. No. 189,414
11 Claims. (Cl. 15—87)

This invention relates to mechanical road sweepers of the type having a side broom or brush for sweeping litter from gutters or against walls into the path of the main transverse broom, and is more particularly directed to the mounting of the side broom or brooms upon such machines.

It is the principal object of the present invention to provide an improved mounting for the side broom of a road sweeper which will permit any one of the said brooms when in operation to move away from the curb in response to increased side pressure or collision with an obstacle without substantially affecting the operation of the machine and to automatically return the broom to a working position upon relief of side pressure or when the obstacle has been cleared.

With the above stated principal object in view, there is provided according to the invention an improved mounting for a side broom of a road sweeping machine comprising a side broom pivotally suspended for angular movement from a longitudinally disposed axis offset relative to the vertical axis or the center of gravity of the broom whereby the latter is retained by road contact in a state of inequilibrium so as to tend to gravitationally move in a direction towards the roadside or curb without obstructing the retractive movement from the latter responsive to obstacle contact.

Thus in operation the broom is maintained in constant curbside engagement responsive to the inclined weight controlled movement described by the broom from its offset pivotal axis, the location of which is such that the broom tends to move constantly in the direction of the curb.

It is a further object of the invention to provide means whereby the height of the broom relative to the roadway can be preset in such a manner that the broom can be raised by the operator to a position for travelling without operating the broom, and can be readily returned to the preselected setting by the operator without any fine adjustment being necessary.

This feature of the invention ensures that the broom will at all times operate efficiently once the height setting has been selected, irrespective of a change of operators driving the vehicle.

With the further stated object in view there is provided height adjusting means for a side broom mounting according to the invention comprising a screw operating a sleeve or stop disposed to retard the downward movement of the broom at a preselected position.

One preferred embodiment of the invention will now be described with reference to the accompanying drawings in which:

FIGURE 1 is a perspective view of the broom mounting upon the road sweeper.

FIGURE 2a is a side elevation of the broom mounting assembly.

FIGURE 2b is a side elevation of the broom height adjusting mechanism.

FIGURE 3 is a front elevation of the broom mounting assembly.

Referring to FIGURE 2a the broom 1 is mounted in a broom frame 2 comprising a pair of side plates 3 fixed in spaced parallelism by a right angle drive gear assembly 4 interposed between the upper end of the plates

2

3 and a bearing housing 5 pivoted on trunnion bearings 6 at the lower ends of the said plates.

5 A main drive shaft 7 enters the side of the gearbox 4 through a universal joint 8 and the drive is transmitted to the broom shaft 9 through a telescopic shaft 10 each end of which is provided with a universal joint 11 to compensate for angular movement of the broom about the trunnions 6.

10 Referring to FIGURE 3, a pair of spaced parallel arms or links 12 (one only is shown) are pivoted at one end 13 to a bracket 14 mounted upon the side of the machine 15 and are pivoted upon bearing 16 at their opposite ends to the side plates 3.

15 The axis of the bearings 16 is located further away from the machine than the centre of gravity of the assembled broom frame 2 so that the broom and broom frame tend to swing away from the machine under the influence of gravity.

20 A roller 17 is mounted between the side plates 3 adjacent the upper ends of the latter and engages a cam track 18 fixed to the machine 15, the said track limiting the movement of the broom away from the machine.

25 A resilient buffer 19 is fixed between the side plates 3 and limits the inward movement of the broom towards the machine.

30 As the broom frame 2 is raised or lowered the links 12 move radially about their pivotal axis 13 and the roller 17 traverses the cam track 18 to retain the broom frame at the same relative angle to the machine as the broom 1 is raised or lowered.

35 A chain 20 is coupled to the broom frame 2 at one end 29 and is passed over a pulley 28 to be connected at the opposite end 21 (shown in FIGURE 2b) to one end of a pair of parallel arms 22, the other end of the said arms being pivoted to the frame of the machine at 23.

40 The ram 24 of a hydraulic cylinder 25 is pivotally connected to the arm 22 at 26 while the cylinder is pivoted to the frame of the machine at 27.

45 A sleeve 30 having a threaded collar 31 fixed to one end, is secured by a pin 32 to a folding crank handle 33 and is rotatable within a bearing 34 mounted on trunnions 35 between the arms 22.

50 A bar 36 has one end retained by a pin 37 in a recessed casting 38a fixed to the frame of the machine, and has upon the opposite end a screwed section 38 engaged within the collar 31. Rotation of the handle 33 moves the collar 31 and sleeve 30 upon the screw 38, whilst the bearing 34 is free to axially move within the limits of the sleeve 30 responsive to actuation of the hydraulic ram 24 associated with the cylinder 25.

55 Referring to FIGURE 3 a hydraulic cylinder 39 is pivotally mounted between the side plates 3, as at 40, and has a ram 41 pivotally connected at 42 between a pair of brackets 43 bolted to the bearing housing 5, so that extension of the ram 41 from the cylinder 39 will angularly move the broom 1 about the trunnion bearings 6 to the position shown in broken lines. With the broom in the latter position the telescopic shaft 10 will have extended to the position shown in broken lines in FIGURE 3.

60 The controls of the hydraulic cylinders 25 and 39 and the crank handle 33 are situated so as to be readily operable by the driver of the vehicle.

65 In operation the broom frame is lowered by the operator when the control of the cylinder 25 is actuated to retract the ram 24 into the cylinder 25 thereby allowing the chain 20 to move over the pulley wheel 28 so that the arms 12 angularly move about the axis 13 until the broom reaches the operating position in contact with or adjacent to the surface of the road.

To further adjust or angle the broom to an efficient

operating position the operator may actuate the controls of the hydraulic cylinder 39 so as to extend the ram 41 and angularly move the broom about the axis of the trunnion bearings 6, the telescopic shaft 10 extending or retracting in response to the actuation of the said cylinder.

As the broom frame is raised or lowered the roller 17 traverses the cam 18, compensating for the outward and inward movement occasioned by the radial movement of the arms 12 about the pivot axis 13.

The extent to which the broom may be lowered is determined by adjustment of the screw 38 relative to the collar 31 upon the sleeve 30, the angular movement of the arms 22 being restricted when the broom is lowered by contact of the bearing 34 with the collar 31 terminating the sliding movement of the said bearing upon the sleeve 30.

By rotating the crank handle 33 the operator can move the screwed collar 31 upon the screw 38 to a predetermined position so as to arrest the downward movement of the broom when the latter is lowered to an operating position.

Actuation of the hydraulic controls to extend the ram 24 and thereby raise the broom, moves the trunnioned bearing 34 along the sleeve 30 while the collar 31 remains undisturbed in the preset position.

Accordingly the operator can readily raise the broom at any time such as when the broom is not required to operate, and lower the broom to the previously preset position when required, this feature of the invention being particularly advantageous when the machine is being operated by different drivers as in shift work.

In such cases a relieving driver has no trouble in bringing the broom into the precise operating position used by the preceding driver.

Referring to FIGURE 3 it will be seen that the pivot axis 16 is located towards the outer edge of the side plates 3 so that the centre of gravity of the broom and broom frame assembly is upon a vertical axis located between the pivotal axes 13 and 16.

Accordingly the broom and broom frame assembly at all times tends to move away from the body of the machine towards the gutter or curb being cleaned.

The extent of outward movement of the broom is limited by the engagement of the roller 17 with the cam surface 18, and the inward movement, by the resilient buffer 19 making contact with the side of the machine 15.

As the broom wears and is lowered towards the ground in order to maintain pressure, the roller 17 takes up a progressively lower position on the contour of the cam surface 18.

As the broom wears it also loses some of its diameter, however, by plotting the shape of the cam surface 18 with the loss of diameter, due to wear, the loss of diameter of overhang can be compensated for.

The roller 17 is flanged on each side so that when engaging the cam 18 the cam is disposed between the flanges. This arrangement resists forces acting head-on to the broom, taking all fore and aft slogger out of the assembly.

When operating, the broom at all times pivots about the axis 16 away from the machine towards the gutter or curb under the influence of gravity, however, should any obstacle block the path of the broom, the resultant pressure upon the broom will cause the latter to move about the axis 16 towards the body of the machine until the obstacle has been passed, whereupon the broom will be gravitationally influenced to resume its former operating position.

When the broom makes contact with an obstacle, the roller 17 will disengage the cam 18 as the broom swings inwardly about axis 16, any extensive inward movement of the broom frame being limited by the contact of the buffer 19 with the body of the machine.

Accordingly, the broom will at all times tend to move away from the machine and thereby make contact with

the curb or road surface to be cleaned, while at all times being free to temporarily move towards the machine should an obstacle be encountered.

We claim:

1. An improved mounting for a side broom from the body of a road sweeping machine, which machine is movable in a given direction of travel, said mounting comprising: an upright support frame, means supporting the side broom from the upright support frame and means suspending the upright support frame and the broom therewith from said body, the latter means including an arm supporting the support frame for pivotal movement about a longitudinal axis extending in the direction of travel of the machine, said broom and support frame having a center of gravity which is offset from said longitudinal axis in a direction towards said body, the broom and support frame thereby being urged under the influence of gravity to pivot about said axis away from said body to a position whereat the broom is adapted for being supported on a surface, said broom tending to move gravitationally in a direction away from the body with the broom in contact with the surface while being freely retractable upon contact with an obstacle.

2. An improved broom mounting as claimed in claim 1 comprising means for raising and lowering the support frame relative to the body of the machine.

3. An improved broom mounting as claimed in claim 2 wherein the means supporting the side broom from the support frame includes means pivotally connecting the broom to the support frame to permit relative angular movement therebetween to enable the broom to conform to the road surface.

4. An improved broom mounting as claimed in claim 3 comprising hydraulic means operatively associated with the upright support frame and the broom to vary the angular position between the support frame and the broom.

5. An improved broom mounting as claimed in claim 4 comprising telescoping drive means coupled to the broom to accommodate angular movement of the broom relative to the support frame while maintaining a driving relation with the broom.

6. An improved mounting for a side broom from the body of a road sweeping machine which is adapted for movement in a given direction of travel, said mounting comprising: an upright support frame including spaced upstanding side plates, means connecting the side broom to the plates, drive means between said plates and coupled to the broom for driving the same, and means connecting the side plates to the body of the machine for pivotal movement about a longitudinal axis extending in the direction of travel of the machine, the last said means including an arm for each side plate supporting the latter for pivotal movement about a second axis extending parallel to the first said axis, said support frame and broom having a center of gravity which is offset with respect to said second axis in a direction towards the machine body whereby the frame and broom are urged under the influence of gravity to move relative to said second axis outwardly to a position whereat the broom is supported on a surface, said arms undergoing angular movement relative to the body as said frame and broom move relative to the first said axis.

7. An improved broom mounting as claimed in claim 6 comprising means connecting the support frame to the machine body to maintain the support frame in a position of constant attitude relative to the body and to permit thereby raising and lowering of the support frame upon angular movement of said arms.

8. An improved broom mounting as claimed in claim 7 wherein said means maintaining the support frame in constant attitude comprises a roller supported from the support frame, and a cam track fixed to the body of the machine and accommodating said roller for movement thereon.

9. An improved broom mounting as claimed in claim 8 comprising flanges on said roller and cooperative with said track to restrict longitudinal movement of the support frame and the broom therewith relative to the machine body.

10. An improved broom mounting as claimed in claim 8 comprising height adjusting means for selectively limiting downward movement of the broom to a preselected lowered position relative to a road surface.

11. An improved broom mounting as claimed in claim 10 wherein said height adjusting means comprises a manually operable screw, a threaded sleeve threadably engaged

on said screw, and stop means connected to the support frame for contacting the sleeve for being limited thereby to terminate downward movement of the broom in accordance with the position of the sleeve on the screw.
